UNITED STATES PATENT OFFICE.

ROBERT D. SCHOONMAKER, OF PLAINFIELD, NEW JERSEY.

PHONOGRAPH.

1,281,671.

Specification of Letters Patent. Patented Oct. 15, 1918.

Application filed April 8, 1918. Serial No. 227,248.

To all whom it may concern:

Be it known that I, ROBERT D. SCHOONMAKER, a citizen of the United States, and a resident of Plainfield, in the county of Union and State of New Jersey, have invented certain new and useful Improvements in Phonographs, of which the following is a specification.

The present invention relates to talking machines, and more particularly to the construction and mounting of the sound-conveying tube or tone-arm employed on such machines.

The main object of the invention is to provide a simple and inexpensive way of mounting a tone-arm on the casing of the talking machine so as to give it the required freedom of movement in planes parallel and at right angles to the surface of the record.

With these and other objects in view, which will more fully appear as the nature of the invention is better understood, the same consists in the combination, arrangement, and construction of parts hereinafter described, pointed out in the appended claims and illustrated in the accompanying drawings; it being understood that many changes may be made in the size and proportion of the several parts and details of construction within the scope of the appended claims without departing from the spirit or sacrificing any of the advantages of the invention.

One of the many possible embodiments of the invention is illustrated in the accompanying drawings, in which—

Figure 1 is a side elevation, partly in section, of a tone-arm constructed in accordance with the present invention; and Fig. 2 is a section taken on line 2—2 of Fig. 1.

In the drawings, the numeral 10 indicates the horizontal top of a talking machine casing, carrying, in the well-known manner, the usual turntable for supporting a disk sound record (not shown). Above the record support, to coöperate with the record, is a suitable sound-box or sound-reproducer, rigidly connected with the free smaller end 11 of a tapering tone-arm 12, with which it communicates. The free end of the tone-arm extends in substantially horizontal direction and the larger end 13 is curved downwardly through an arc of about 90 degrees.

The larger end of the tone arm extends into a tubular body 14, which projects above

the casing top 10, and is provided with a flange 15, preferably integral therewith, said flange resting upon the upper surface of the casing top and being held thereon in fixed position, for instance, by screws 16. The tubular body registers with an opening 17 in the casing top, the said opening, in turn, communicating with the usual horn that is disposed within the casing. The outer diameter of the larger end of the tone-arm is slightly smaller than the inner diameter of the tubular body 14, thereby permitting of a movement of said tone-arm in a vertical plane.

For supporting the tone-arm upon the tubular body 14, there is provided within the said tubular body a spider 18, having a centrally arranged aperture 19, through which extends the reduced end 20 of a spindle 21. A portion of this spindle is disposed above the said spider, and extends through a circular aperture 22 in a spider 23, the latter being fixed to the larger end of the tone-arm. The diameter of the aperture 22 is substantially larger than the diameter of the body portion of the spindle 21, thereby permitting of a free movement of the tone-arm upon the said spindle. To the spindle 21 is fixedly attached an upwardly extending vertical support 24, made of spring wire and carrying upon its upper free end a cylindrical head 25. This head is seated in a recess 26 in the tone-arm, a screw 27, extending through the said tone-arm into the said head, serving to hold the tone-arm upon its support. This screw bears loosely against the tone-arm, so as to permit the latter to turn around its support.

The wire 24 is heavy enough to counter-balance the weight of the tone-arm and the sound-box or reproducer carried thereby, but, at the same time, is resilient enough to permit the tone-arm to swing in planes at right angles to the surface of the record, as the needle on the sound-box is caused to swing up and down.

The operation of this device is as follows:—The sound-box, in following the track of the record, causes the tone-arm to swing in a plane parallel to the record around the head 25 of its support. Inasmuch as this head is yieldingly supported, it is obvious that the tone-arm is adapted to follow oscillations of the needle in a vertical plane, as shown in dotted lines in Fig. 1 of the drawings. The resilient support

causes, however, the needle on the sound-box always to remain in contact with the record.

What I claim is:—

- 5 1. In a talking machine, the combination with a tubular body, of a spider fixed therein, a flexible upwardly extending support on said spider having a cylindrical head on its free upper end, and a tubular tone-arm extending into said tubular body and rotatably mounted upon said head, the inner diameter of said tubular body being larger than the outer diameter of the portion of the tone-arm extending into said tubular body.
- 10 2. In a talking machine, the combination with a tubular body, of a spider fixed therein, an upwardly extending wire on said spider having a cylindrical head on its upper

free end, and a tubular tone-arm extending into said tubular body and rotatably mounted upon said head, the inner diameter of said tubular body being larger than the outer diameter of the portion of the tone-arm extending into said tubular body.

3. In a talking machine, the combination with a tubular body, of a tubular tone-arm, and flexible and elastic supporting means carried by said tubular body in engagement with said tone-arm permitting the latter to rotate with respect to said tubular body and also to move in a vertical plane in relation thereto.

Signed at New York, in the county of New York, and State of New York, this 3rd day of April A. D. 1918.

ROBERT D. SCHOONMAKER.
